UNITED STATES PATENT OFFICE.

THEODOR M. A. SURY, OF CLEVELAND, OHIO.

VENDING APPARATUS.

No. 824,831.

Specification of Letters Patent.

Patented July 3, 1906.

Application filed March 23, 1905. Serial No. 251,896.

To all whom it may concern:

Be it known that I, THEODOR M. A. SURY, a citizen of the United States, residing at Cleveland, in the county of Cuyahoga and State of Ohio, have invented new and useful Improvements in Vending Apparatus, of which the following is a specification.

This invention relates to a coin-controlled apparatus for delivering measured quantities of a beverage or other liquid.

The object of the invention is to provide an apparatus of this kind which is comparatively simple of construction and efficient and reliable in operation.

The preferred embodiment of the invention is illustrated in the accompanying drawings, in which—

Figure 1 is a central vertical longitudinal section of a vending apparatus embodying my invention, the parts appearing in their normal position. Fig. 2 is a sectional plan view of the apparatus on the line 2 2 of Fig. 1. Fig. 3 is a detail view of one of the valves controlling the outlet of fluid from the storage-receptacle. Fig. 4 is a detail view of the guard-slide; and Fig. 5 is a similar view of the guide block or piece which tilts the coin and releases it from the guard-slide, so that it may drop through the coin-outlet into the coin-receptacle.

Referring now more particularly to the drawings, wherein like reference characters designate corresponding parts throughout the several views, the numeral 1 represents a casing which may be of any preferred form, construction, and dimensions and which is preferably made of metal, galvanized or granitized to prevent the same from rusting under the action of moisture or contained ice used to keep the liquid to be vended cool. This casing may be surrounded by a non-conducting jacket 3 to prevent the same from becoming unduly affected by external temperatures, the said casing 1 having a bottom 4, forming a base common to both the jacket and casing, and a lid or cover 5, closing the top of the casing and which may be provided with a metallic lining 6. The lid or cover 5 is preferably hinged or pivoted to the jacket, so as to be conveniently opened, and may be held closed by any preferred type of locking means. The casing forms an inclosure for a storage-receptacle 7, designed to contain the beverage or liquid to be vended, which re-

ceptacle may be provided with supporting legs 8 to rest upon the base of the casing and hold it suitably centered therein and at a proper elevation. The upper end of the receptacle 7 is closed by a cover 9, which may be removed when it is desired to clean or replenish the same with liquid.

Depending from the bottom of the receptacle 7 is a measuring vessel 10, which may be of any capacity to receive and measure a determined amount of liquid to be vended for a prescribed coin. This receptacle is provided with an inclined bottom 11, terminating in a horizontal valve-seat 12, from which leads a discharge-stem 13, to which is connected a discharge-pipe 14, extending to the exterior through the front wall of the casing 7 and terminating at its outer end in a discharge-nozzle 15. The measuring-receptacle is closed by a cap or cover-plate 16, removably secured to the bottom of the storage-receptacle in any preferred manner and having an inlet 17 rising therefrom and terminating in a frusto-conical valve-seat 18.

The ejection of liquid from the measuring-receptacle 10 to the pipe 14 is controlled by a frusto-conical valve 19, which is adapted to rest upon the seat 12 and inclined bottom walls 11 of said receptacle and is attached to the lower end of an operating-stem 20, passing upwardly through the measuring vessel and storage-chamber and also through a sleeve or tubular stem 21, carrying at its lower end a frusto-conical valve 22, adapted to engage the seat 18 and controlling the admission of liquid to the measuring vessel 10 from the storage-receptacle 7. The sleeve or tubular stem 21 forms a guide for the stem 20 and is itself guided by the body portion of a spider or armed brace 23, fixed upon the interior of the receptacle 7, through which it loosely passes. The upper end of the stem 20 is directly connected to the inner end of a controlling-cord 24, by which it may be lifted to open the valve 19, while the tubular stem 21 is provided at its upper end with a lug 25, slotted to receive a pin 26 on one end of a rocking arm or lever 27, centrally pivoted upon a rod 28, suitably fixed to the receptacle 7 and connected at its opposite end by a short cord or flexible connection 29 to the controlling-cord 24.

The normal position of the parts is shown in Fig. 1, from which it will be seen that the

valve 22 is open to allow liquid to pass from the storage-receptacle 7 to the measuring vessel 10, while the valve 19 in the latter is closed to prevent the discharge of the measured quantity of liquid therein therefrom to the outlet-pipe 14. When the cord 24 is pulled upon, it raises the stem 20, thereby opening the valve 19 to permit the contents of the vessel 10 to discharge and at the same time through the connection 29 rocks the arm 27, thereby depressing the stem 21, so as to force the valve 22 to closed position, the connections being so proportioned and disposed that the valve 22 will close slightly in advance of the period of opening the valve 19, so as to cut off the flow of liquid from the receptacle 7 to the measuring vessel 10 just before the contents of said vessel begin to discharge through the outlet controlled by the valve 19. Hence when the cord 24 is actuated a prescribed or measured amount of liquid only will be permitted to pass through the pipe 14 and to be supplied to the purchaser or consumer.

25 The cord 24 passes at its upper end toward the front of the casing over suitable guide-pulleys 30 and thence downwardly through a guide-tube 31, communicating at its lower end with a casing-section 32, secured upon the interior of the casing 1 in line with an opening 33 therein and containing a guide-pulley 34, around which the lower end of the cord 24 passes and is guided.

Secured to the outer side of the casing 1 in line with the opening 33 is a casing-section 35, which forms with the casing-section 32 a receptacle for a guard-slide 36, consisting of a long and narrow block or plate, the rear portion of which projects through the opening 33 into the casing-section 32 and is provided with an eye 37, to which the lower end of the cord 24 is attached. The forward portion of the guard-slide projects into the rear portion of the casing-section 35 and is provided with a vertical lug or offset 38, formed with a forwardly-projecting bifurcated or slotted guide 39 overhanging the outer and forward portion 40 of the slide. This slotted guide 39 receives a coin-guide block or piece 41, secured to the upper portion of the rear half of the casing-section 35 in rear of a coin-inlet slot 42, formed therein, and above a coin-outlet slot 43 and is provided with a beveled or inclined guide-face 44, extending from the rear edge of the slot 42 to a point above the rear edge of the slot 43. The slide 36 is normally pressed outward by a spring 44', located in the casing-section 32, and has its front portion 40 and free ends of the arms of the bifurcated portion 39 arranged just in rear of the slot 42, so that a coin deposited in said slot will drop into the rear half of the casing-section 35 in advance of said portions of the slide and behind the inner operating end of a plunger 46, as hereinafter described. The

bifurcated portion 39 permits the slide to have movement without interference from the coin-guide block 41, as will be readily understood.

The plunger 46 slides through openings in the front wall of the casing-section 35 and a partition 47, dividing said casing into front and rear portions, in the rear portion of which the slide, as before described, is located. The outer end of this plunger is provided with a suitable knob or finger-piece 48, by which it may be conveniently pushed inwardly, while the inner end of said plunger is provided with an upper beveled face 49 to coöperate with the beveled face 44 of the guide-block 41 to properly position the coin to discharge through the outlet 43 and to prevent interference with its discharge by the slide 36. The coins discharging through the outlet 43 fall into a coin-receptacle 50, disposed below the casing-section 35 and provided with a suitable door 51, which may be locked by any preferred type of fastener.

When a coin is deposited in the slot 42, it falls between the inner end of the plunger 46 and the front portion of the guard-slide 36, and thus operatively connects the plunger with the guard-slide, as normally the plunger may be moved inwardly without actuating said slide, as the plunger will simply play between the portions 39 and 40 of the slide. With a coin in position the inward movement of the plunger 46 will through the coin transfer motion to the slide 36, thus pulling down upon the cord 24 and operating the valves to discharge liquid, as previously explained. As the slide moves rearwardly the coin is held between the same and the plunger until the coin strikes the inclined surface 44 of the coin-guide block 41, when the coin will be tilted and will rest in tilted position with its upper face against said portion 44 and its lower face against the beveled surface 49 of the plunger, so that the coin will be brought to a horizontal position to drop downward through the slot 43 when the slide 36 has reached the limit of its inward movement and before it can be projected outwardly under the action of its spring 44 to interfere with the downward feed of the coin after the release of the plunger 46. The plunger 46 is restored to its normal position upon being released by a spring 46', one end of which is secured thereto, and the other end bears against the partition 47, the spring thus lying in a chamber formed in the forward or outer end of the casing-section 35, as clearly shown in Fig. 1.

From the foregoing description, taken in connection with the accompanying drawings, the construction and mode of operation of the invention will be understood without a further extended description.

Changes in the form, proportions, and minor details of construction may be made

within the scope of the invention without departing from the spirit or sacrificing any of the advantages thereof.

Having thus described the invention, what is claimed as new is—

1. In a liquid-vending apparatus, the combination of a storage-receptacle, a measuring vessel communicating therewith, a valve normally open and controlling the flow of liquid from the receptacle to the vessel, a valve normally closed and controlling the outlet of measured liquid from the vessel, stems attached to said valves, one of said stems being movable within the other stem, an operating device attached to one stem, and a reversely-operating connection connecting said operating device with the other stem.

2. In a liquid-vending apparatus, the combination of a storage-receptacle, a measuring vessel communicating therewith, a valve nor-

mally open and controlling the flow of liquid from the receptacle to the vessel, a valve normally closed and controlling the outlet of measured liquid from the vessel, stems attached to said valve, one of said stems being movable within the other stem, a sliding spring-retracted controlling device, a flexible operating connection between said device and the stem of the normally closed valve, an intermediately-pivoted lever linked at one end to the stem of the normally open valve, and a connection between the other end of the lever and the said flexible operating connection.

In testimony whereof I affix my signature 35 in presence of two witnesses.

THEODOR M. A. SURY.
